CLAIM

I claim the ornamental design for a cowling of a goalie skate, as shown and described.

DESCRIPTION

FIG. 1 is a perspective view of a cowling of a goalie skate according to the present design; the illustrated cowling is for a left foot, the cowling for a right foot being a mirror image of the one for a left foot;

FIG. 2 is a top plan view of the cowling of a goalie skate of FIG. 1;

FIG. 3 is a front elevational view of the cowling of a goalie skate of FIG. 1;

FIG. 4 is a left side elevational view of the cowling of a goalie skate of FIG. 1;

FIG. 5 is a rear elevational view of the cowling of a goalie skate of FIG. 1; and,

FIG. 6 is a right side elevational view of the cowling of a goalie skate of FIG. 1.

The bottom view is omitted since the bottom of the cowling is unornamented. The broken lines shown in the figures form no part of the design and are for illustrative purposes only.
